UNITED STATES PATENT OFFICE.

LÉON DARRASSE AND ETIENNE DARRASSE, OF PARIS, AND LUCIEN DUPONT, OF VINCENNES, FRANCE.

MANUFACTURE OF SYNTHETIC CAMPHOR BY MEANS OF A LIQUID CATALYST.

No Drawing. Application filed June 1, 1921, Serial No. 474,190, and in France June 9, 1920.

The fixation of organic acids with essence of turpentine in order to obtain bornyl or isobornyl esters is known since the work of Bouchardat and Lafont.

5 This reaction has been the object of several patents having for their purpose the industrial manufacture of synthetic camphor, each patent corresponding to an acid or a group of acids having special properties. Among the acids the use of which has already been mentioned in previous patents, one can mention particularly oxalic acid, sebatic acid, and phthalic acid or its derivatives. Of all these acids the one most particularly interesting owing to its low cost and its small molecular weight is evidently oxalic acid.

A first patent relating thereto is French Patent No. 303,812 dated 17th September, 20 1900, to the Ampere Electro Chemical Company and its first patent of addition No. 83 dated 1st February, 1902.

If one refers to the processes described in 25 patents relating to the use of oxalic acid, it is noticed that the essential feature of these processes consists in the application of heat to a mixture of oxalic acid and of essence of turpentine. This mixture is generally raised to a temperature of 120° to 30 130° C. One obtains in this manner turpentine and isobornyl esters of oxalic and formic acids.

The action of heat at the temperature of 35 the reaction causes therefore a decomposition of free or combined oxalic acid, giving bornyl formate. Moreover, owing to hydrolysis, esters and terpinolic compounds are formed at that temperature the yield being reduced thereby. This process as 40 described in the previous patents gives a poor yield, both as concerns the essence of turpentine, which is transformed and polymerized, and the oxalic acid, which is partly decomposed.

45 A second and more interesting patent is the French Patent No. 393,478 dated 19th August, 1908, to the Chemische Fabrik auf Actiengesellschaft (vorm. E. Schering). In this patent, Schering claims the use of a 50 catalyst to promote the reaction of oxalic acid on turpentine. He uses exclusively metallic chlorides as catalyst, under the name of "contacting agent", and, among these chlorides, he particularly selects aluminium chloride; he also mentions chloride

of antimony, and phosphorus and zinc chlorides. In his patent Schering states that, eventually, one can use a diluting agent such as benzol or carbon tetrachloride, but without insisting on this point. the said diluting agent being added rather to moderate the reaction, which is particularly energetic with such an active agent as aluminium chloride since he mentions that it is necessary to moderate it by artificial cooling when the temperature reaches 70° C.

55 With the present invention, while oxalic acid is used for the manufacture of bornyl ester, all the drawbacks pointed out above can be eliminated; almost the whole of the turpentine taking part in the reaction being utilized. As to the uncombined turpentine it is not altered and can be used over again either for the same purpose or any other use to which turpentine can be put.

75 The means by which these improvements are obtained consist in using a liquid catalyst. Among the catalysts giving the best results mention must be made of chlorinated and brominated hydrocarbons, and, among these, methylene chloride, chloroform, carbon tetrachloride, ethylene chloride, ethylene bromide and especially the series of the acetylenic chlorinated hydrocarbons, and particularly, in this series, tetrachlorethane. Benzene and acetone, on the other hand, appear to be very inferior catalysts. These various catalysts exhibit very different properties, first as to the speed 80 of the reaction and then as to the quality of the products, chloroform is more rapid than carbon tetrachloride, but both are slower than the tetrachlorethane and the trichlorethylene.

85 The temperature at which the action takes place is most important for several reasons: the first being the decomposition of the oxalic acid owing to the rise in temperature. This decomposition is practically nil till 115° C. and becomes more important as the 90 temperature is raised; at 120°-150° C. it is relatively important and may reach 20% of the weight of the oxalic acid used. On the other hand the rise of temperature accelerates the reaction to an extraordinary degree. A reaction which takes 100 hours at 75° C. to utilize the whole of the oxalic acid used, is completed in 20 minutes at 140°-150° C. A last reason of great importance, which also favours a relatively 105 110

high temperature is to be found in the quality of the products obtained. Below 100° C. the oxalic ester obtained from the reaction is pasty and contains products the 5 saponification of which give liquid terpenes.

From 115° C., the ester so obtained becomes hard and crystalline; it is composed almost exclusively of neutral bornyl oxalate, and its saponification gives a solid 10 berneol eminently adapted to the manufacture of camphor. One finds again here in this case the influence of temperature, comparable to that of the well known action of 15 gaseous hydrochloric acid on essence of turpentine.

The manner in which the process is carried out consists in heating together to a temperature of 115° to 120° C. the mixture 20 of liquid catalyst, essence of turpentine and anhydrous oxalic acid, $C_2O_4H_2$.

For catalysts of relatively low boiling point such as chloroform, trichlorethylene, carbon tetrachloride, the ratio of the weight of the essence of turpentine and the catalyst 25 must be such that the ebullition of the mixture takes place at the required temperature. Even with a very volatile body like the tetrachloride of carbon it is necessary to have a mixture containing a large proportion of 30 the tetrachloride in order that the ebullition should begin and remain at 125° C. One will even easily attain 130°-140° C.

Oxalic acid is slightly soluble in the mixture, it dissolves gradually during the 35 reaction and entirely disappears at the end. A small proportion of acid bornyl oxalate is formed approximately 2 to 5% of the weight of the oxalic acid used, but the principal body formed during the catalysis, except 40 bornyl formate is neutral oxalate. The two carboxylic groups of oxalic acid enter in combination contrarily to what takes place in the processes which are based on the esterification of turpentine with sebacic 45 acid, and also to what takes place with the various other acids derived of the phthalic series which have been used for the same purpose and with which acid esters are obtained.

Neutral bornyl oxalate, $C_2O_4(C_{10}H_{16})_2$, is 50 not decomposed at a temperature sensibly above 100° C. It is a nonvolatile body; it can therefore be easily separated from the turpentine in excess either by steam distillation, or by distillation in vacuum; it decomposes at a high temperature. Bornyl oxalate is very easily saponified, even by very dilute aqueous solutions of soda. The product of the saponification is isoborneol and 55 sodium oxalate; from the latter, oxalic acid can be easily recovered.

The catalytic action is clearly demonstrated by the difference between the times required to complete the reaction at a temperature in the vicinity of 100°. For comple-

tion, the reaction requires 30 hours with tetrachlorethane, 50 hours with chloroform and over 60 hours with carbon tetrachloride: at a temperature of 140°, it is terminated in half an hour with tetrachlorethane. It is 70 also clearly marked by the differences between the products obtained. This, besides the novelty of the new catalysts used, such as the tetrachlorethane, plainly differentiate the process from those described in the 75 above mentioned patents.

As mentioned above, all the acids can be used, with the help of the liquid catalysts which we mention, with a noteworthy improvement in the yield as compared with 80 their yield without a catalyst.

We have tried the different organic acids: formic, acetic, butyric, sebacic, benzoic, salicylic, etc. However, for the various reasons: cost, small molecular weight, ease of 85 separation of the formic ester from turpentine, facility of saponification of bornyl oxalate and convenience of recovery of oxalic acid, we have given preference to the latter 90 oxalic acid.

In a similar manner, although the chlorinated compounds of acetylene, trichlorethylene and tetrachlorethane, have a more rapid action, we prefer the use of carbon tetrachloride as catalyst, owing to its lower 95 cost and the greater ease with which it is separated from turpentine.

An example is given below of this improved process:

A mixture of 40 parts of turpentine free from water, 20 parts of carbon tetrachloride free from water and 5 parts of anhydrous oxalic acid is heated by steam to ebullition with a reflux condenser.

If necessary, a little tetrachloride is first allowed to distil out in order to ensure that the internal temperature of the boiling liquid is 115° C. the reflux condenser is put in action and the ebullition is continued until the oxalic acid is completely dissolved; when the latter has entirely disappeared, which requires 7 to 8 hours, the remaining liquid is distilled first in vacuum, and subsequently with steam.

The distillate contains tetrachlorethane and the turpentine in excess. One can, either separate them by rectification, or add to the mixture a proportion of turpentine equivalent to that which has entered into combination in order to begin a fresh operation.

The residue of the distillation consists chiefly of bornyl oxalate. The quantity of esterified oxalic acid is not less than 95% of the acid used. The weight of bornyl oxalate obtained is approximately four times the weight of the combined oxalic acid. This bornyl oxalate is saponified subsequently in a soda bath in the usual manner. The saponification is swift.

The borneol is collected by filtration of the solution of sodium oxalate. It can be also carried off by steam distillation, it is then obtained in a cleaner state. The oxidation of this borneol by one of the known methods leads to camphor, directly, with good yields.

We claim:

1. In the process of making camphor from turpentine by converting the pinene into bornyl ester, saponifying the ester to produce borneol and oxidizing the borneol to camphor; the improvement which comprises acting on turpentine with oxalic acid and a liquid catalyst consisting solely of a halogenated open chain hydrocarbon at a temperature that is substantially the boiling point of the mixture.
2. In a process of making camphor from turpentine by converting the pinene into bornyl ester, saponifying the ester to produce borneol and oxidizing the borneol to camphor; the improvement which comprises acting on turpentine with oxalic acid and a liquid catalyst consisting solely of a halogenated open chain hydrocarbon at the boiling point of the mixture, and controlling the temperature of the reaction by the quantity of turpentine present.
3. In the process of making camphor from turpentine by converting the pinene into bornyl ester, saponifying the ester to pro-

duce borneol and oxidizing the borneol to camphor; the improvement which comprises acting on turpentine with oxalic acid in the presence of a halogenated open-chain saturated hydrocarbon acting as a sole catalyst for the reaction between said acid and turpentine at a temperature, at which the mixture boils, to produce bornyl oxalate.

4. In the process of making camphor from turpentine by converting the pinene into bornyl ester, saponifying the ester to produce borneol, and oxidizing the borneol to camphor; the improvement which comprises acting on turpentine with oxalic acid in the presence solely of a liquid halogenated open chain hydrocarbon at a temperature not less than 100° C., to produce bornyl oxalate.

5. In the process of making camphor from turpentine by converting the pinene into bornyl ester, saponifying the ester to produce borneol and oxidizing the borneol to camphor; the improvement which consists in acting on turpentine with oxalic acid in the presence of tetrachlorethane at a temperature between 100° and 150° C. to produce bornyl oxalate.

In testimony that we claim the foregoing as our invention, we have signed our names.
